UNITED STATES PATENT OFFICE.

HARRY HAMMOND HOWELL, OF HOPE, ARKANSAS.

METER-BOX.

1,156,530.

Specification of Letters Patent.

Patented Oct. 12, 1915.

Application filed September 23, 1913. Serial No. 791,388.

To all whom it may concern:

Be it known that I, HARRY HAMMOND HOWELL, a citizen of the United States, residing at Hope, in the county of Hempstead and State of Arkansas, have invented a new and useful Meter-Box, of which the following is a specification.

This invention relates to meter boxes or housings particularly designed for use in connection with water meters.

One of the objects of the invention is to provide a simple, durable and efficient device of this character which is sufficiently strong not to crush when subjected to the weight of heavily loaded vehicles; which has a cover provided with a simple lock designed to prevent tampering by unauthorized persons, and which is so shaped and proportioned as to inclose the service cock with the meter, thereby to eliminate entirely the extra expense heretofore involved in providing service boxes.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown. In said drawings: Figure 1 is a vertical section through two sections of a meter box and showing a meter and service cock housed therein, the cover being locked in closed position. Fig. 2 is a section on line A—B Fig. 1 looking upward. Fig. 3 is a plan view of a portion of the cover. Fig. 4 is a section on line C—D Fig. 3, the pivot pin and button being shown in elevation. Fig. 5 is a perspective view of the key.

Referring to the figures by characters of reference 1 designates the body of the box or housing, the same being formed in a single casting and preferably substantially elliptical in cross section. The upper edge of the housing is formed with an annular enlargement 2 provided with a rabbet 3 constituting the seat for the cover 4 of the meter. This cover, which is formed in a single casting, is provided with reinforcing ribs 5 and a lip 6 is extended inwardly from the wall 1 close to the rabbet 3 and is adapted to be engaged

by an ear 7 formed on the lower surface of the cover 4, this ear being so shaped as to extend under or lap the lip 6, as shown in Fig. 1. Formed in the cover 4 at a point diametrically opposed to the ear 7 is a circular depression 8 having a web 9 extending across the center thereof, one end of this web being overhung by a retaining lug 10 formed integral with the wall of the depression. 65 Segmental outlet openings 11 are formed in the bottom of the depression 8 at opposite sides of the web 9 and constitute outlets through which dirt and other material is free to drift so as not to clog the depression 70 8 and interfere with the rotation of the button hereinafter referred to.

A stem 12 is mounted for rotation within the web 9 and is provided at its upper end with an angular head 13 seated on the web 9. 75 Riveted or otherwise secured to the lower end of the stem 12 is a button 14, one end of which is upturned, as shown at 15 so as to present an inclined end 16 to the inclined surface of a lip 17 formed on the inner side 80 of the wall of body 1 close to the rabbet 3 at a point diametrically opposite the lip 6. In fact the two lips 6 and 17 are duplicates.

For the purpose of rotating the button 14, a key of novel form is provided. This 85 key, which has been illustrated in Fig. 5, includes a stem 18 having a handle 19 at one end while its other end is formed with a socket 20 the seat in which is so shaped as to receive the head 13 and to fit snugly thereon. This socket is partly surrounded by a flange 21 the ends of which are spaced apart a distance slightly greater than the width of the lug 10. Thus it will be seen that by placing the key above the recess 8 and lowering it thereinto so that the lug 10 will be received between the ends of flange 21, the socket 20 will become seated on the head 13 and the key can then be rotated. This will result in rotating the head 13 so as to bring 90 the button 14 out of engagement with lip 17. At the same time flange 21 moves under lug 10 and thus prevents the removal of the key from the cover until the button has been turned back to its normal position. 95 Stop pins 22 and 23 are provided upon the bottom face of the cover 4 for the purpose of limiting the movement of the button 14. Stop 23 is adapted to be contacted by the button when said button is brought into engagement with lip 17 while stop 22 is contacted by the button after said button has 100 105 110 115

been removed from engagement with the lip. With this arrangement it will be seen that the key can be used for lifting the cover after the cover has been unfastened and there is no danger of the cover dropping off the key. Obviously, the cover can be quickly placed in position on the box or body 1 and the button 14 can be swung into engagement with either lip 6 or 17, according to the position of the cover on the box. Ear 7 can likewise engage either of the lips which may be adjacent thereto. With the ear 7 in engagement with one of the lips and button 14 in engagement with the other lip, it is obviously impossible to remove the cover until the button has been disengaged from its lip.

Importance is attached to the fact that the meter box is elliptical for the reason that it is thus possible to house the water meter E and the service cock F in the box where they can both be reached conveniently, thus doing away with the necessity of providing a special service box for the cock F. Furthermore it will be noted that the box 1 is formed, in its bottom, at the ends of its longest diameter, with deep recesses or notches 24. Where only one meter box 1 is used for housing the meter, these recesses 24 receive the pipes leading to and from the meter but it is to be understood that where two or more of the boxes 1 are placed upon each other, as shown in Fig. 1, only the notches or recesses 24 of the lower section are utilized, these receiving the pipes leading to and from the meter, as shown in Fig. 1. Where two or more boxes are placed upon each other, the rabbets of the lower

boxes receive the lower edges of the next adjoining boxes thereabove so that lateral or longitudinal displacement of the boxes relative to each other is prevented. By providing this arrangement of boxes, the housing can be made of any depth desired. Importance is attached to the fact that the openings 11 in the recess 8 permit dirt and moisture to sift out of the recess so that, when the key is inserted into the recess, there will be no accumulations to interfere with the proper placing and manipulation of the key.

What is claimed is:—

The combination with a cover having a depression therein and a key retaining lug integral with the cover and overhanging the depression, of a head mounted for rotation in the depression, a button under the cover and revoluble with the head, means extending from the cover for limiting the rotation of the button, a key having a socket for the reception of the head, said key being insertible into the depression, and a flange extending partly around the key adapted to receive the lug between the ends of the flange when the key is inserted into the depression, said flange coöperating with the lug to prevent withdrawal of the key when the button is turned out of locking position.

In testimony that I claim the foregoing as my own, I have hereto affixed my signature in the presence of two witnesses.

HARRY HAMMOND HOWELL.
